US00D827432S

(12) United States Design Patent (10) Patent No.: US D827,432 S
(45) Date of Patent: * Sep. 4, 2018

(54) CASE

(71) Applicant: Apple Inc., Cupertino, CA (US)

(72) Inventors: Jody Akana, San Francisco, CA (US); Bartley K. Andre, Palo Alto, CA (US); Shota Aoyagi, San Francisco, CA (US); Anthony Michael Ashcroft, San Francisco, CA (US); Jeremy Bataillou, San Francisco, CA (US); Daniel J. Coster, San Francisco, CA (US); Danielle De Iuliis, San Francisco, CA (US); M. Evans Hankey, San Francisco, CA (US); Julian Hoenig, San Francisco, CA (US); Richard P. Howarth, San Francisco, CA (US); Jonathan P. Ive, San Francisco, CA (US); Duncan Robert Kerr, San Francisco, CA (US); Matthew Dean Rohrbach, San Francisco, CA (US); Peter Russell-Clarke, San Francisco, CA (US); Benjamin Andrew Shaffer, San Jose, CA (US); Mikael Silvanto, San Francisco, CA (US); Christopher J. Stringer, Woodside, CA (US); Eugene Antony Whang, San Francisco, CA (US); Rico Zörkendörfer, San Francisco, CA (US)

(73) Assignee: Apple Inc., Cupertino, CA (US)

() Term: 15 Years

(21) Appl. No.: 29/572,804

(22) Filed: Jul. 29, 2016

Related U.S. Application Data

(63) Continuation of application No. 29/501,046, filed on Aug. 29, 2014, now Pat. No. Des. 763,104.

(57) CLAIM

The ornamental design for a case, as shown and described.

DESCRIPTION

FIG. 1 is a top front perspective view of a case showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the case that form no part of the claimed design.

The dot-dash broken lines in the figures show boundaries that form no part of the claimed design.

1 Claim, 3 Drawing Sheets
